(57) **CLAIM**

The ornamental design for an ambient LED lighting display synchronisation set-top box as shown and described.

DESCRIPTION

FIG. 1 is a top perspective view of an ambient LED lighting display synchronisation set-top box, showing my new design;

FIG. 2 is a bottom perspective view thereof;

FIG. 3 is a rear elevation view thereof;

FIG. 4 is a front elevation view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 6 Drawing Sheets
